UNITED STATES PATENT OFFICE.

BELTON TATTNALL HAMILTON, OF CHURCH END, FINCHLEY, ENGLAND.

CARBURETER.

1,234,756.

Specification of Letters Patent. Patented July 31, 1917.

Application filed September 4, 1914. Serial No. 860,258.

To all whom it may concern:

Be it known that I, BELTON TATTNALL HAMILTON, residing in Church End, Finchley, Middlesex, England, have invented certain new and useful Improvements in Carbureters for Internal-Combustion Engines, of which the following is a specification.

It has already been proposed to admit to the engine either a mixture of petrol and air or a mixture of petroleum and air or a mixture of these two substances jointly from separate carbureting or vaporizing devices by the agency of separate valves which can be initially set for that purpose, into a common passage controlled by a separate throttle valve and it has, moreover, been suggested for the purpose of supplying either petroleum vapor and air or petrol vapor and air to provide a three-way valve which is moved in an axial direction by the governor for controlling the maximum quantity of the individual mixtures and angularly by hand whereby one of the mixtures may be gradually cut off while the admission of the other is gradually increased.

Now the carbureter according to this invention enables one or several different fuel mixtures to be admitted separately or jointly likewise by producing the mixtures in several individual carbureters separately, but in contra-distinction to the known arrangements provision is made of several separate substantially rectangular or rhomboidal ports for admitting the individual mixtures to the engine which are so arranged with regard to separate rectangular or rhomboidal outlets leading from the mixing chambers of the carbureters as to be movable thereon in two directions parallel to the corresponding edges of the ports so that by displacement of the separate admission ports they are set to predetermine the maximum quantity of each individual mixture to be admitted therethrough and that by movement at will in the other sense by means of a common member the quantities of all individual mixtures actually admitted are varied simultaneously in constant ratio in all the admission ports.

In some cases I may carry this relative adjustment to such an extent that it is possible to prevent any one or more of the admission or throttle ports from being opened at all when their common member is actuated for the purpose of effecting the adjustment.

A constructional example of the invention is illustrated in the accompanying drawings showing a carbureter arrangement hereinafter referred to as a bi-fuel carbureter in which two different kinds of fuel, for instance, petrol and paraffin are to be used in the engine by the simultaneous provision of two carbureters, one adapted to form the mixture from petrol and the other from paraffin.

Figure 1 illustrates an end view of this carbureter.

Fig. 2 is a vertical section of Fig. 1 taken on the line A—B.

Figs. 3, 4 and 5 indicate diagrammatically the use of the invention in the carbureter for only one fuel, for instance, petrol, Fig. 3 showing the position for slow light running, Fig. 4 the position at half throttle, and Fig. 5 at full throttle.

Figs. 6, 7 and 8 illustrate diagrammatically the use of the carbureter for the simultaneous admission of both fuels, for instance, paraffin and petrol, Fig. 6 indicating the position of the openings for slow light running, Fig. 7 at half-throttle and Fig. 8 at full throttle.

The construction of the two carbureters constituting together the bi-fuel carbureter is *per se* well known being substantially of the type referred to in the specification of my prior British Letters Patent No. 24544/1909. Each of these carbureters forms an individual unit. For the purpose of this invention these two carbureters are rigidly connected or formed integral one with the other. It will of course be understood that any desired number of such individual carbureters could be combined in a similar manner. These carbureters are designated *c* and *c'* and as already stated they are identical in construction, while for the understanding of this invention it should be assumed that the carbureter *c* is supplied with petrol and the carbureter *c'* with paraffin, and that the mixtures of these two fuels are readily formed in the usual manner in the mixing chamber of each carbureter separately. Each carbureter is provided with a float chamber 1 to which the respective fuel is supplied by way of a bore 2 automatically controlled by a needle valve 3. Air is supplied to each carbureter by way of a socket 4. In each carbureter the fuel, controlled by means of a further needle valve 5, together with the air, flows by

way of a mixing tube 6 and passages 7 to a mixing chamber which in the case of the carbureter *c* is designated by *a* and in the case of the carbureter *c'* by *b*. The valve 8 admitting air to the mixing chamber in each case is constituted by a substantially conical body and its seat or counterpart 9 has a determined preferably conoidal curvature so that a mixture of particularly desirable properties is obtained in each carbureter in the well known manner.

A common chamber or housing 10 preferably of cylindrical shape is connected with the casing of each carbureter by means of a spherical socket 11, which sockets as shown are integral with the housing 10. The housing 10 is provided with a central opening 12 confined by a flange 13 adapted to be screwed to the induction pipe of the engine. Arranged within this casing 10 is a valve 14 having the form of a cylindrical sleeve which is snugly fitted in but is shorter than the longitudinal dimension of the housing 10 so as to be capable of longitudinal dis- placement therein.

This cylindrical sleeve forms in this case the common member and is provided with two separate slots or throttle ports 15, 16, preferably of rectangular or rhomboidal shape as shown in Figs. 3 to 8 of the accompanying drawings, one to register when desired with quadrangular outlet openings 17 of the mixing chamber *a* of the carbureter *c* and the other 16 with the similar outlet opening 18 of the mixing chamber *b* of the carbureter *c'* so that by longitudinal or axial displacement of the sleeve 14 the required relative proportions of the throttle ports to be brought into register with the respective outlet passages are in this case simultaneously set. For the purpose of axially displacing or setting the throttle ports the sleeve may be provided with an axial extension 19 by means of which the driver is able to adjust it with the aid of a suitable lever 20 or other known contrivance in a well known manner. For this purpose the external end of the axial extension 19 is provided, for instance, as shown, with a grooved collar 21 and the lever 20 is provided with two lateral lugs engaging by means of pins 22 in the groove in the collar 21 so that by the driver exerting a pull on a flexible connection 23 or the like the lever 20 is turned about its pivot 24 to any desired extent and thereby moves the throttle valve 14 axially to a corresponding extent. The sleeve at the same time is rotatable so as simultaneously to bring into register with the outlet passages above referred to, the throttle ports adjusted as afore-mentioned, through which the individual mixtures are admitted, that is to say, the combined supply of the mixtures to the engine. To this end the throttle valve as

shown is preferably actuated by a rotary arm 25 which by means of a boss or collar 26 is mounted on the square-shaped extension 19 and is suitably actuated by the driver.

It will of course be understood that the preliminary adjustment of the throttle ports with the same effect may be obtained by rotary movement and the regulation of the mixture quantity to the engine by an axial displacement if desired without departing from the spirit of the invention.

The size and position of the individual slots or throttle ports 15, 16 in the sleeve may of course be so chosen as to render it possible by the displacement of the throttle valve to cause the outlet of one chamber of one carbureter to be entirely closed automatically as soon as the outlet from the other mixing chamber is entirely open, or moreover, by suitably shaping or positioning the ports in the throttle valve or further by suitably constructing the latter or its actuating mechanism so as to provide for a combined rotary and axial movement to be imparted to the throttle valve for the adjusting purpose, the admission areas of the ports in the throttle valve may be varied to any different degree relatively to one another as will be readily understood from an inspection of Figs. 3 to 8, in which as already explained the throttle ports 15, 16 in the common member are shown diagrammatically by way of example in various positions with regard to the outlet openings 17 and 18 so that either only one individual carbureter or both carbureters jointly may be employed to deliver their individual mixtures from their mixing chambers *a* *b* in regulable quantities, to the engine.

What I claim and desire to secure by Letters Patent is:

1. In a multiple fuel carbureter for the admission to the engine jointly of different fuels in the form of individual mixtures the combination with a plurality of carbureters having substantially rectangular individual mixture outlets terminating in a common casing, of a common controlling member in the said casing and provided with a corresponding number of rhomboidal admission ports so arranged with regard to the said separate outlets as to be movable thereon in two directions parallel to the corresponding edges of the said ports so that by the displacement in one direction of the said separate admission ports they are set to predetermine the maximum quantity of each individual mixture to be admitted therethrough and by movement in the other direction the quantities of all individual mixtures actually admitted are varied simultaneously in constant ratio in all the admission ports, substantially as set forth.

2. In a multiple fuel carbureter for the admission to the engine jointly of different

fuels in the form of individual mixtures the combination with a plurality of carburetors having individual substantially rectangular mixture outlets of a common casing for the whole of the said mixture outlets, a common controlling sleeve removable in the said casing with separate admission ports for the said outlets, means for displacing the said sleeve longitudinally whereby the maximum area of each admission port to be brought into register with its corresponding mixture outlet is predetermined, and means for displacing the said sleeve in angular direction enabling any desired portion of that predetermined maximum opening of each admission port 16 to be brought into actual register for all the ports simultaneously, substantially as described.

In testimony whereof I have affixed my signature in presence of two witnesses.

BELTON TATTNALL HAMILTON.
